[57] CLAIM

The ornamental design for a combination bicycle component clamp and multi-purpose tool, as shown and described.

DESCRIPTION

FIG. 1 is a left front perspective view of a combination bicycle component clamp and multi-purpose tool showing a first embodiment of my new design;
FIG. 2 is a right rear perspective view thereof;
FIG. 3 is a left side elevational view thereof;
FIG. 4 is a front end elevational view thereof;
FIG. 5 is a rear end elevational view thereof;
FIG. 6 is a right rear perspective view of a combination bicycle component clamp and multi-purpose tool showing a second embodiment of my new design;
FIG. 7 is a left front perspective view thereof;
FIG. 8 is a left side elevational view thereof;
FIG. 9 is a front end elevational view thereof; and,
FIG. 10 is a rear end elevational view thereof.

FIG. 1

FIG. 2

FIG. 3

FIG. 5

FIG. 4

FIG. 6

FIG. 7

FIG. 8

FIG. 10

FIG. 9
